FILTER FOR CIGARETTE HOLDERS

Janette A. Howard, Bronxville, N. Y.

Application March 25, 1950, Serial No. 151,931

5 Claims. (Cl. 131—187)

1

This invention relates to a filter for a cigarette holder, the particular holder being more fully shown in my co-pending application filed of even date herewith bearing Serial No. 151,932.

One of the objects of this invention is to provide a filter which may be easily inserted into a cigarette holder and yet will effectively filter certain contaminants from cigarette smoke which otherwise would enter the mouth.

Another object of this invention is to provide a filter which may be easily inserted in the cigarette holder and withdrawn therefrom.

Another object of this invention is to provide a filter for a cigarette holder which may be disassembled and new parts substituted as found necessary or desirable.

Another object of this invention is to provide a cigarette holder which will provide a cork tip for use in the mouth.

With these and other objects in view, the invention consists of certain novel features of construction, as will be more fully described and particularly pointed out in the appended claims.

In the accompanying drawings:

Figure 1 is a sectional view of the filter shown assembled in a cigarette holder;

Figure 2 is a section on line 2—2 of Figure 1;

Figure 3 is a section on line 3—3 of Figure 1;

Figure 4 is a section on line 4—4 of Figure 1;

Figure 5 is an exploded view showing in perspective the various parts which enter into the holder and filter.

In proceeding with this invention I provide a tubular cartridge which may be inserted into a holder and cover this cartridge with cork, and mount at one end of the cartridge a mouthpiece which is also covered with cork and which affords a means for holding the holder in position with the barrel of a cigarette holder.

With reference to the drawings, 10 designates the barrel portion of a cigarette holder which is tapered at one end as at 11 and receives in this end a cigarette 12 shown in dotted lines. This holder 10 is usually of metal although it may be made of non-metallic materials as desired. A threaded surface is provided at the other end of the holder as at 13 for holding the filter within, and a band 14 is provided which may serve as an ornament on the outer surface of the holder and may be slid along the holder to various positions.

The filter comprises a removable cartridge in the form of a metal tube or shell 15 which forms a tubular chamber of the filter and is provided with a resilient cork covering 16 over its outer

surface extending substantially the length thereof. The inlet end of the filter is provided with an end wall 17 with a plurality of openings 18 therethrough, there being shown four in number (see Figure 2). The outside diameter of the cork covering 16 is such that in positioning the filter into the bore of the holder 10 the said covering will be compressed to provide a snug fit and prevent passage of air therealong.

A mouthpiece 20 may be formed of some hard material such as bone or hard rubber and may have a covering of cork 21 over its outer surface and is provided with a bore 22 centrally located therethrough. In some cases, however, the entire mouthpiece may be formed of cork or cork composition. The inner end 23 of this mouthpiece is of reduced diameter providing a shoulder 24 between this reduced diameter and the outer mouth engaging portion 25. About this inner projecting portion 23 there is a sack 26 of a resilient material which may be flexible rubber or any of the newer synthetic rubberlike materials. A plurality of openings 28 are provided in the tapered end of this sack, there being shown five in this particular illustration. This resilient sack is stretched and placed over the projecting portion 23 of the mouthpiece 20 and then the mouthpiece with the sack thereon is inserted into the metal shell 15 and has a tight fit therewith, the shoulder 24 engaging the edge of shell 15. The shoulder extends out beyond the chamber portion of the filter and a ferrule 27 may be provided having an inwardly extending flange 28 to engage the opposite side of said shoulder, while its threads 29 may engage the threads 13 for holding the filter within the tubular holder 10.

In order to keep the sack expanded so that air may pass therethrough, I have provided a resilient member designated generally 30 and which comprises a pair of arms 31 and 32 secured together by the arm 32 having a tongue 33 bent over the surface of the arm 31 so as to bind the two parts together. These attached ends of this resilient member may be inserted into the bore 22 by forcing the same into this bore so as to support the resilient member in position. These arms 31 and 32 are in the form of resilient spring parts which flare outwardly due to the inherent set of the stock so that the ends 34 and 34' of this spring member will press against the sack adjacent the openings 26 so as to hold the sack expanded and the openings free for the passage of air and smoke therethrough. However, these openings are of such size as to catch any solid particles which may otherwise pass into the sack.

In operation, when drawing in at the mouth-piece end of the filter, smoke and air from the cigarette will pass through the inlet openings 18 into the chamber 35 and there solid particles will tend to settle out or be caught in the more restricted portions between the sack and the shell or about the openings 26, while the smoke and air will pass through the sack and into the mouthpiece. As the contaminants of the smoke collect, the chamber 35 will gradually become filled with the contaminants and after a certain length of use which may be determined by experience the shell 15 and its end wall 17 may be removed and replaced or the sack 25 may be removed, the sack and spring member cleaned 15 and the sack replaced.

The cork tip provides a good mouthpiece and for feminine use may be colored as desired.

I claim:

1. A smoking device comprising an outer tubular member open at each end thereof and externally threaded at one end portion and having a straight bore extending inwardly from the said threaded end thereof, a reduced bore extending inwardly from the other end thereof of a size to receive a cigarette therein, and a tapered relatively short bore extending between said straight and reduced bore portions, a tubular shell open at one end and having an apertured wall at the other end providing a chamber, said tubular shell being of a length substantially equal to the length of said straight bore and received therein in sealing engagement with the walls of said straight bore portion and with the apertured wall of said tubular shell abutting against the wall of the said tapered bore portion at the intersection thereof with said straight bore portion, a mouthpiece having an end portion thereof extending into said tubular shell and provided with an annular shoulder one side of which abuts against the open end of said tubular shell and the end of said tubular member, threaded means abutting against the other side of said shoulder and engaging said externally threaded portion to detachably secure said tubular shell and mouthpiece to said tubular member, and a sack 35 extending into said chamber and frictionally attached to said mouthpiece at the end portion thereof within said tubular shell and providing a snug frictional engagement between said mouth

piece and said tubular shell at the said reduced portion of said mouthpiece and adjacent wall of said shell, said sack having a plurality of small openings therein at the free end portion thereof whereby smoke drawn from the cigarette will pass through said chamber and sack to be filtered as passing therethrough.

2. A smoking device as in claim 1 further comprising a V-shaped resilient member secured at 10 the apex of the V in the bore of the said mouthpiece and extending into said sack to keep it expanded.

3. A smoking device as in claim 1 further comprising a resilient compressible covering frictionally engaging said tubular shell and of a size when under slight compression to be snugly received within said straight bore.

4. A smoking device as in claim 1 wherein said threaded means for securing said mouthpiece 20 and said tubular shell to said tubular member comprises a ferrule threadingly engaging said tubular member and having a flange extending into engagement with the other side of said shoulder.

5. A smoking device as in claim 1 in which the inner apertured wall of said tubular shell is spaced from the reduced bore portion a distance to provide a stop for engaging and limiting the distance the cigarette may be inserted into said 30 tubular member.

JANETTE A. HOWARD.
